(57) **CLAIM**

The ornamental design for an eyelet, as shown and described.

DESCRIPTION

1. Eyelet

1.1 is a perspective view of an eyelet showing a new design;

1.2 is a side view thereof;

1.3 is a top view thereof;

1.4 is a bottom view thereof;

1.5 is a side view thereof; and

1.6 is a cross sectional view thereof taken from line A-A in 1.3.

The letters 'A's and the arrows in reproduction 1.3 are only for representing a part of cross section and form no part of the claimed design.
